UNITED STATES PATENT OFFICE.

LOUIS WOLF, OF NEW YORK, N. Y.

DESIGN FOR A HAND-BAG.

49,201.

Specification for Design.

Patented June 13, 1916.

Application filed March 31, 1916. Serial No. 88,178. Term of patent 3½ years.

To all whom it may concern:

Be it known that I, LOUIS WOLF, a citizen of the United States, and a resident of New York, in the county and State of New York, have invented a new, original, and ornamental Design for Hand-Bags, of which the following is a specification, reference being had to the accompanying drawing, forming part thereof.

The figure is a plan view of a hand-bag, showing my new design.

The design comprises a series of superposed cascades, ripples, waves, billows, festoons, hammocks, etc., arranged on the central vertical line of the bag, of equal sizes, or of varying sizes.

I claim:

The ornamental design for a hand-bag, as shown and described.

LOUIS WOLF.
